VIBRATING EQUIPMENT

Lewis E. Soldan, San Diego, Calif.

Application January 7, 1948, Serial No. 961

5 Claims. (Cl. 74—87)

1

This invention relates to improvements in vibrating equipment. More particularly this invention relates to an improved vibrating device that can be used to impart controlled vibrations to bulky objects and materials.

It is therefore an object of the present invention to provide an improved vibrating device that can be used to impart controlled vibrations to bulky objects and materials.

In the construction and operation of vibrating devices it is customary to mount rotatable eccentrics in bearings on opposite sides of the deck or supporting surface of the vibrating device, and to pass a connecting shaft through those eccentrics in such a way that the shaft keeps the eccentrics in registry. This shaft is customarily spaced a short distance above the deck or supporting surface of the vibrating device, and in most instances it does not interfere with the operation and use of the vibrating device. In some instances, however, the object or materials to be placed on the supporting surface or deck of the vibrating device are quite large and bulky; and in those instances the connecting shaft may prevent movement of the materials or objects along the supporting surface or deck of the vibrating device, and may even prevent the placing of the materials or objects on the supporting surface or deck of the vibrating device. This, of course, limits the versatility and capacity of the vibrating device by limiting the size of the objects and material which can be supported and vibrated by the vibrating device. For example, where the vibrating device is to be used to shake out the molding sand or cores from castings, the presence of the connecting shaft limits the size of the castings which can be accommodated by the vibrating device. For these various reasons the presence of connecting shafts, which extend between and support the eccentrics of vibrating devices, can be objectionable. The present invention obviates these objections by providing cross-jack shafts which are radially spaced from the rotatable eccentrics carried by the opposite sides of the vibrating devices and which can be positioned below the supporting surfaces or decks of the vibrating devices or can be positioned sufficiently far above the supporting surfaces or decks of the vibrating devices to permit those supporting surfaces or decks to receive large and bulky objects and materials. It is therefore an object of the present invention to provide a vibrating device with a cross-jack shaft that is radially spaced from the eccentrics of that device and is spaced from the supporting surface or deck of that device.

2

To be efficient, vibrating devices must have the eccentrics thereof maintained in constant synchrony and register with each other; and those devices must also be capable of permitting relative adjustment of those eccentrics to vary the throw of those eccentrics. Where this is done, the vibrating devices can be set to provide various desired "throws" and can maintain those "throws" without unbalancing of the vibrating devices. The present invention makes this possible, and still provides the advantages of unusually large capacity for the vibrating devices by having the cross-jack shafts spaced radially from the eccentrics while holding those eccentrics in synchrony and registry. It is therefore an object of the present invention to provide a vibrating device with a cross-jack shaft that will permit the eccentrics to operate in registry with each other and will still permit relative adjustment of each eccentric.

Where vibrating devices are used to support large and bulky materials or objects, those devices must be made quite large, and thus must be made quite heavy. The amount of power required to vibrate those devices becomes larger as the weight of the vibrating devices increases, and it is therefore desirable to reduce the weight of the vibratable portions of the vibrating devices as much as possible. The cross-jack shaft of the present invention makes such a reduction in weight possible by having the cross-jack shaft supported separately from the vibratable portions of the vibrating device. In this way, no power is required to carry and vibrate the weight of the cross-jack shaft. It is therefore an object of the present invention to provide a vibrating device with a cross-jack shaft which is separately supported from the vibratable portions of the vibrating device.

40 The construction contemplated by the present invention has rotating parts spaced away from the rotatable eccentrics; and those rotating parts must be driven by chains and gears. Such chains and gears must be provided with adequate lubrication to prevent excessive wearing thereof, and they also must be covered to protect the operators of the vibration devices from the dangers inherent in exposed gears and chains. The present invention provides housings or casings for the gears and chains, and causes those housings to perform the dual function of providing adequate lubrication for the rotative equipment and of providing protection for workers and passersby. It is therefore an object of the present invention to provide a housing for a vibrating device that encloses the chains and gears of that device and

assures protection for workers and passersby and also acts as an oil reservoir.

In some instances the objects or materials to be vibrated are so large they cannot be accommodated on the largest of vibrating devices. In such instances, it is necessary to correlate several vibrating devices together and to position those devices so they can provide support for the objects or materials to be vibrated. In such instances it is desirable that all of the vibrating devices be held in synchronism with each other so controlled vibrations of the desired amplitude can be imparted to the objects or materials which are supported jointly by the several devices. The present invention makes this possible by utilizing a number of cross-jack shafts which are adjacent a number of vibrating devices, and which are so correlated together that each of the cross-jack shafts is in registry with the cross-jack shafts of every other vibrating device. It is therefore an object of the present invention to provide a plurality of vibrating devices which are provided with cross-jack shafts that are held for conjoint rotation.

Other and further objects and advantages of the present invention should become apparent from an examination of the drawing and accompanying description.

In the drawing and accompanying description several preferred embodiments of the present invention are shown and described but it is to be understood that the drawing and accompanying description are for the purposes of illustration only and do not limit the invention and that the invention will be defined by the appended claims.

In the drawing,

Fig. 1 is a partially broken-away perspective view of a vibrating device that is made in accordance with the principles and teachings of the present invention, and that device has a cross-jack shaft which is positioned beneath the deck of the vibrating device.

Fig. 2 is an enlarged cross sectional, end view of the eccentrics and driving mechanism of the vibrating device of Fig. 1, and it shows those eccentrics enclosed within a modified form of a housing.

Fig. 3 is an enlarged side elevational view of the modified housing or casing, shown in Fig. 2, for the eccentrics of the vibrating device of Fig. 1.

Fig. 4 is a perspective view of another vibrating device which is provided with a cross-jack shaft, and that cross-jack shaft is positioned above the deck of that vibrating device.

Fig. 5 is a perspective view of a number of vibrating devices which are positioned adjacent to each other and are connected for conjoint actuation.

Fig. 6 is a cross sectional end view of another form of vibrating device that is made in accordance with the principles and teachings of the present invention, and

Fig. 7 is a cross sectional end view of yet another vibrating device that is made in accordance with the principles and teachings of the present invention.

Referring to the drawing in detail, the numeral 10 generally denotes a body structure for a vibrating device; and that body structure has upper and lower screening decks 11 and 12. These decks extend between and are supported by opposite side walls 13 and 14. A supporting standard 15 is provided adjacent each end of the side walls 13 and 14, and those standards

are suitably secured to a suitable base or floor, not shown. Each of the standards 15 carries on its upper end 16 a block 17 of resilient material, such as rubber or the like; and a suitable bearing plate 18 is interposed between the bottom of the block 17 and the top 16 of the standard 15. An eye bolt 19, having its eye portion 20 below the plate 18 and between the legs of the standard 15, is projected upwardly through a relatively large opening 21 in plate 18, through a central bore in the resilient block 17, and through a central opening 22 in a bearing plate 23 that is seated on top of the block 17. The bolt 19 is threaded along its upper end for receiving a nut 24, and this nut bears against and engages the bearing plate 23. Rotation of the nut 24 relative to the eyebolt 19 will permit attainment of the desired positioning of the eye portion 20 of bolt 19 relative to the supporting standard 15. Once this positioning has been accomplished, further relative rotation between nut 24 and eye bolt 19 is prevented by the lock nut 25. With this arrangement, the eye bolt 19 will be permitted to reciprocate vertically while being confined against undue lateral tilting. The legs of the standard 15 straddle stub shafts 26 which project outwardly from the side walls 13 and 14 of the body structure 10, and those stub shafts are held by supporting cables 27 which pass through the bolt eye 20 and around the stub shafts 26.

Although not fully shown in the drawing, standards 15, resilient blocks 17, bearing plates 18 and 23, nuts 24 and 25, stub shafts 26, and cables 27 are provided adjacent the ends of side wall 14 of the vibrating device. The view of those elements is obscured by the body structure 10; but those elements cooperate with their visible counterparts to resiliently support the body structure 10 and permit it to vibrate.

A pair of flexible cables 30, only one of which is shown, are secured to the lower portions of the side walls 13 and 14 of the body structure 10; one cable 30 being at each end of the body structure 10. Those cables are secured intermediate their ends to the base or other support on which the standards 15 rest; and thus the cables 30 hold the body structure 10 against side sway. The flexibility of the cables 30 permits ready gyration and vibration of the body structure 10 upwardly, downwardly, forwardly and backwardly, but the relative inextensibility of the cables 30 prevents side sway of the body structure 10.

A cross-jack shaft 28 is disposed transversely below the screening body structure 10; and that shaft has one of the opposite ends thereof secured to a driving pulley or belt sheave 29. The pulley or sheave 29 can be connected to a driving unit such as an electric motor or the like, not shown, as by belts which extend between and connect the motor and the sheave 29; and this motor can cause rotation of the cross jack shaft 28. Rotation of the jack shaft 28 is converted to gyroscopic and vibratory motion for the body structure 10 through vibration-imparting mechanisms located in the housings 32 on the side walls 13 and 14 of the body structure 10; although only one of the two housings 32 is shown in the drawing. The housing 32 for the side wall 14 is obscured by the body structure 10, but it is the same as the housing 32 for the side wall 13. The housings 32 are secured directly to the side walls 13 and 14, and they are spaced radially from the cross-jack shaft 28. Housings 33 are provided on each side of the body structure 10, and those housings

extend from the ends of cross-jack shaft 28 to the housings 32.

The housings 32 are generally cylindrical in form and they are provided with circumferentially extending flanges 110. These flanges, as shown particularly in Fig. 2, are made as separate annuli and are then secured to the cylindrical portions of the housings 32 by a weld. However, where desired, the housings 32 and flanges 110 can be made unitary in form, as by casting them of light-weight metal. The flanges 110 are provided with a number of circumferentially spaced openings 111, and those openings receive bolts 112 which seat in generally circular plates 34 that are secured to side walls 13 and 14 by bolts 36.

The plates 34 support the stub shafts 35, and those shafts support pairs of heavy-duty roller thrust bearings 37. The inner races of the adjacent pairs of bearings 37 are relatively spaced by an intermediate ring 38, and the bearings 37 are held in position on the shafts 35 by shoulders 39 on those shafts and by retaining plates 40 which are removably attached to the end faces of the stub shafts 35 by bolts 41. Journaled on the outer races of bearings 37 are the hub sections 42 of discs 43, and those discs have axially projecting hub portions 44 with external surfaces 45 that are eccentric to the axes of the stub shafts 35. Other discs 46 are provided with hub sections 47 that have internal surfaces which receive and telescope over the hubs 44 of the discs 43. The internal surfaces 48 of hubs 47 and the external surfaces 45 of hub portions 44 are circular, and thus the discs 43 and 46 can be rotated relative to each other; but those surfaces are eccentric to the axes of stub shafts 35 so relative rotation of discs 43 and 46 can vary the combined eccentricity of those discs. To facilitate relative shifting of the discs 43 and 46, the discs 43 may have slots of suitable angular extent that will receive the bolts 49 therethrough; or, as is presently preferred, the discs 43 may be provided with a series of bolt holes 50 that can receive the bolts 49 which are mounted in discs 46.

Frame plates 51 are provided on opposite sides of the body structure 10, and those plates support the cross-jack shaft 28 through anti-friction bearings 52. The lower ends of frame plates 51 are secured by brackets 52a, to the opposite ends of a tubular housing 52b that encloses the shaft 28; and the housing 52b is suitably secured to the base or floor, not shown, on which the vibrating device is mounted. For example, the support for housing 52b, of the cross-jack shaft 28, may include arms 52c which are pivotally mounted at their ends 52d, by resilient sleeves 52e, to the portions 52f of the base on which the standards 15 rest. Such mounting permits cross-jack shaft 28 to move relative to base 52e without any need of a lubricated pivot that would require servicing. The other ends 52f of the arms 52c encircle the housing 52b; but the ends 52f are spaced from the housing 52b by bearing rings 52g which are formed of suitable resilient material. The bearing rings 52g, the sleeves 52e, and the arms 52c support the weight of the housing 52b while permitting a limited amount of movement of the housing 52b when the vibrating device is being started or stopped. While the vibrating device is running, the cross-jack shaft 28 will rotate concentrically without appreciable vibration.

The frame plates 51 extend upwardly to the vicinity of stub shafts 35, and the upper ends 53 of those plates support housings 54 for anti-friction bearings. The bearings in housings 54

support shaft elements 55 which have their axes off-set from, or eccentric to, the axes of stub shafts 35. The shaft elements 55 are rotated by the cross-jack shaft 28 through the medium of sprockets 56 which are keyed to shaft 28, sprocket chains 57, and sprockets 58 which are keyed and bolted to the shaft elements 55. The sprockets 56 and 58, and the sprocket chains 57, are enclosed within the casings 33, which casings are removably attached to the frame plates 51 by bolts; and as a result the sprockets 56 and 58 and the sprocket chains 57 cannot injure workers or passersby.

A flange-like extension 60 is formed integrally at the inner end of each of the shaft elements 55, and those extensions are secured at their peripheries to the end faces of the hub sections 47 of discs 46 by stud bolts 61. In this way, rotation of shaft elements 55 causes rotation of the discs 46 and 43; and since the shaft elements 55 are held in synchronism and registry by the cross-jack shaft 28, the discs 43 and 46 at each side of the body structure 10 will also be held in registry and synchronism.

With this arrangement, the discs 46 and 43 will begin to rotate eccentrically as the jack shaft 28 starts to rotate, thus causing a slight eccentric movement of the housing 52b. This eccentric movement of the housing 52b will cease, as will the eccentric movement of discs 46 and 43, when the vibrating device gets up to speed; and thereafter the jack shaft 28, the shaft elements 55, and discs 46 and 43 will run concentrically while the body structure 10 moves eccentrically. The amplitude of the eccentric movement of body structure 10 may be varied between its minimum and maximum limits by removing the bolts 49, rotating the discs 43 and 46 relative to each other, and then reinserting the bolts 49 to lock the discs 43 and 46 in their new position. The relative position which discs 43 and 46 occupy in Fig. 2 is the position of maximum eccentricity; and this position provides the greatest amplitude of "throw" for the body structure 10. Relative rotation of one hundred and eighty (180) degrees between discs 43 and 46, which rotation can be facilitated by extending the bolt slots or the bolt holes 50 over an arc of one hundred and eighty (180) degrees, will bring the axes of shaft elements 55 into the axes of the stub shafts 35 for minimum "throw." Any desired amplitude of vibration between minimum and maximum settings can be attained by setting each of the discs 43 at the right angular position relative to the discs 46. Suitable markings can be provided on the peripheries of discs 43 and 46 to indicate the amount of eccentricity at any particular setting.

The discs 43 and 46 are provided with eccentric weights 62 and 63, respectively; and those weights assist in dynamically balancing the rotating parts of the vibrating device. The weights 62 and 63 rotate with the discs 43 and 46, and they are movable relative to each other during changes in the relative position of discs 43 and 46. In this way, the position of the weights is adjustable so the weights can balance the vibrating device at all given eccentricities. The weights 62 and 63 are preferably set relative to discs 43 and 46 so the weights are adjacent each other when the discs are angularly disposed to provide maximum amplitude of vibration. At settings of lesser amplitude of vibration, the weights will be circumferentially spaced apart.

The housings 32 not only serve to protect the

passersby and workers from harmful contact with the rotating discs 43 and 46, but they also assist in the lubrication of the rotating parts. The housings 32, have circular recesses which carry circular gaskets 114 that are pressed into sealing engagement with the supporting plates 34 and thus the housings 32 can contain and hold oil. Oil can be introduced into the housings 32 through the covers 31 or filling holes 65, shown particularly in Fig. 2; the holes 65 being normally closed by threaded plugs. The oil can be drained from housings 32 through threaded openings that are normally closed by plugs 64. The circular faces of the housings 32 have circular openings 66 therein that receive shaft elements 55, and those openings are slightly larger than the compensating rings 69 on shaft elements 55 while being considerably smaller than the oil slingers 71 on those shaft elements. The compensating rings 69 have circular outer peripheries and circular inner peripheries; but the peripheries and eccentric to each other. As a result when the inner peripheries 68 of the compensating rings 69 are concentric with the axes of shaft elements 55, the outer peripheries of those rings are eccentric relative to those shaft elements. Consequently, whenever the discs 43 and 46 are shifted relative to each other, the rings 69 must be shifted to keep the exterior of rings 69 concentric with the openings 66. Suitable markings are provided on the adjacent edges of rings 69 and bearing housings 54 to facilitate an angular shifting of rings 69 which just equals the angular shifting of discs 43 and 46. While the shifting of rings 69 does add one more step to the process of adjusting the eccentricity of the vibrating device, it is of material value because it makes possible considerable reductions in the size of openings 66, thus preventing appreciable oil leakage through those openings. In the event any oil passes through openings 66, that oil will strike oil slingers 71 and be thrown outwardly against the interiors of recessed cover plates 70. Openings 116 are provided in housings 32 adjacent the bottoms of cover plates 72; and oil lodging in cover plates 70 will run back into housings 32 through the openings 116. The central openings in the cover plates 70 will be concentric with the openings 66 in housings 32, and those openings can be made as small as possible by reason of the compensating rings 69. If any oil does pass along shaft elements 55 through openings 66, that oil will be thrown outwardly by oil slingers 71 and will not reach the central openings in the cover plates 70.

Proper lubrication of the bearings 37 is assured by providing V-shaped oil troughs or guide channels 72 on the inner surfaces of the casings or housings 32. These troughs 72 will cooperate with the radially-extending T-irons 67 which are secured to the outer faces of the modified housings 32, shown in Figures 2 and 3, to stiffen the housings 32. Such T-irons are not necessary, as indicated by their absence in Fig. 1, but they do strengthen the housings 32. The principal function of troughs 72 is to assist lubrication of the bearings 37, and those troughs do that by catching some of the oil, which is splashed about in housings 32, directing that oil to the vertically extending portions 73 of the troughs, and then discharging the oil adjacent the conical portions of shaft elements 55. The oil, discharged at this point, will cling to the conical portions of shafts 55 and will be moved radially outwardly by centrifugal force until it strikes the frusto-conical

plates 74, carried on the shaft flanges 60; and thereafter the oil will move through transverse passages 75 in flanges 60. The passages 75 will conduct the oil to the races of the roller bearings 37; and the oil that passes through the bearings 37 will drop downwardly between the hubs of discs 43 and the supporting plates 34 to the lower portions or sumps 76 of the casings 32.

The housings 33, like the housings 32, also perform several functions since they protect workers and passersby from contact with the sprockets 56 and 58 and the sprocket chains 57, and since they also facilitate the lubrication of those sprockets and chains. In addition, the housings 33 perform the additional function of tightening the sprocket chains 57. This tightening of the sprocket chains is made possible by making the exterior and interior surfaces of bearing housings 54 eccentric to each other. Where this is done, rotation of the bearing housings 54 relative to the frame plates 51 will move the frame plates 51 upwardly or downwardly relative to the shaft elements 55, thus varying the tension in sprocket chains 57.

The sprocket chains 57 will extend down into the bottom of housings 33 and will pick up the oil which gravitates to those bottoms. That oil will then be carried upwardly by the chains 57; some of it being transferred directly to sprockets 58, and some of it dripping off of the chains 57 as those chains move through the casings 33. Much of the oil that drops off of the sprockets 58 and the chains 57 will be caught by the generally V-shaped gutters 118 which are secured to the plates 51 and extend down toward the cross-jack shaft 28. As the oil reaches the bottoms of the gutters 118 it will drip onto the deflecting plates 119 which are secured to the housings 33; and those deflecting plates will direct the oil onto conical sections of sprockets 56. Thereafter, centrifugal force will move the oil radially outwardly along those conical sections until it reaches the frusto-conical plates 120 carried by sprockets 56. These plates will direct the oil into the passages 121 that are formed in sprockets 56; and the oil will flow through those passages and onto the races of bearings 52.

The housings 32 and 33 perform still another function; and that is to resist torsional forces which may be created during starting, stopping or running of the vibrating device. In the absence of sizable resistance to such forces, the cross-jack shaft 28 and its housing 52b would tend to move relative to the body structure 10 during acceleration or deceleration of the vibration-imparting mechanism. This movement is largely avoided by use of the torsion-resisting housings 32 and 33.

Fig. 4 illustrates a vibrating device wherein the cross-jack shaft is spaced above rather than below the body structure. That body structure is generally denoted by the numeral 80, and it has a screening surface 81 and side walls 84 and 94. The side walls 84 and 94 carry housings 93 that enclose the vibration-imparting mechanism; and the side walls also carry attaching brackets 85. The brackets 85 have openings therein that receive rods 83, and those rods extend upwardly to an overhead supporting structure 82. To avoid confusion in the drawing, only a small part of the structure 82 was shown; but that structure extends over the four corners of the body structure 80 and supports each of the rods 83. The rods 83 pass through spaced openings in the structure 82, pass through openings in

washers 90 that have spherical surfaces on the under sides thereof, through resilient blocks 86 of rubber or the like, and through washers 89. The upper ends of the rods 83 are provided with threads 87, and those threads receive and hold the nuts 88. The spherical surfaces of the washers 90 seat in brackets 92 which have spherical seating surfaces. With this arrangement, the rods 83 can slide smoothly relative to the structure 82 while resiliently supporting the body structure 80. This permits undampened vibration of the body structure 80 and the materials or objects supported thereon.

The housings 93 are largely similar to the housings 32 of the vibrating device of Fig. 1; and the housings 122 are similar to the housings 33. A jack shaft assembly, generally denoted by the numeral 95, extends between the housings 122; and that assembly includes the cross-jack shaft 96 and the tubular shaft housing 97. The housing 97 is provided with brackets that receive the lower ends of helical springs 98; and the upper ends of those springs are secured to the supporting structure 82. These springs carry most of the weight of the jack shaft assembly 95, thus freeing the body structure 80 of that weight.

Fig. 5 illustrates diagrammatically a plurality of vibrating devices 100, each of which may be of the general form and character shown in Fig. 1. These vibrating devices are positioned adjacent each other and they can receive and impart vibrations to large objects or materials. Each of the vibrating devices 100 has two housings 102 on the opposite sides thereof to enclose the vibration-imparting mechanisms, and a housing 104 extends downwardly from each of those housings. The housings 102 are similar to the housings 32, and the housings 104 are similar to the housings 33. Gross-jack shaft assemblies 103 extend between the lower ends of the housings 104, and those assemblies maintain the vibration-imparting mechanisms of each vibrating device 100 in registry and synchronism. Housings 106 extend between one end of each jack shaft assembly 103 and a coordinating jack shaft assembly 101. The jack shaft assemblies 103 keep the vibration-imparting mechanisms of each vibrating device 100 in registry, and the coordinating jack shaft assembly 101 keeps all of the jack shaft assemblies 103 in registry. In this way, all of the vibrating devices 100 can be made to vibrate as a single unit, or any two or more of them can be made to vibrate as a unit.

It is important to note that in each of the several arrangements of apparatus shown, no part of the gyratory mechanism and its drive extends within or through the material-receiving space of the body structure; thus the present invention avoids any interference between the vibration-imparting mechanism and the materials or objects placed in the body structures. Moreover, the jack shafts and the drive connections to the gyratory mechanism are supported independently of the body structure; thus the weight of the drive is not added to the gyratory mechanism itself. Consequently, the function of the gyratory mechanism is thereby improved since it may be more closely controlled than has heretofore been possible and it can be operated with less power.

In Fig. 6 a modified form of vibrating device is shown; and that vibrating device is somewhat simpler than the device shown in Fig. 2. That device has circular plates 134 which bear against

and are secured to the side walls 113 of the body structure. The circular plates 134 are secured to the side walls 113 by bolts 105 that extend through openings in the side walls 113 and seat in threaded openings in the plates 134. The circular plates 134 carry and support stub shafts 135; and those shafts are provided with reinforcing webs 136. Anti-friction bearings 137 have their inner races supported on the stub shafts 135; and spacing rings 138 are placed between the inner races of adjacent bearings 137. The bearings 137 are held in engagement with stub shafts 135 by end plates 140; and the end plates 140 are secured to the stub shafts by suitable bolts. The outer races of the bearings 137 fit within the hubs 142 of discs 144, which hubs and discs are welded or otherwise secured together. End rings 146 are carried by the hubs 142, and those end rings keep the bearings 137 and discs 144 in assembled relation. Discs 148 are releasably secured to the first discs 144 by bolts 149 and nuts 150; and those bolts pass through slots or openings in discs 144. The discs 148 have hubs 151, and those hubs telescope over and receive the hubs 142; the outer and inner surfaces of the hubs 142 being circular but being eccentric to each other, and the outer and inner surfaces of the hubs 151 being circular but being eccentric to each other. With this arrangement, adjustment of the discs 144 relative to the discs 148 can vary the amount of eccentricity of discs 148 relative to the stub shafts 135.

Shaft elements 153 are secured to the hubs 151 by bolts 154, and those elements project outwardly through openings 156 in the housing 158. This housing is secured to the circular flange of webs 136 by bolts 160, and is thus secured to the circular plates 134. Weights 62 and 63 are secured to the discs 144 and 146 respectively, and those weights maintain the dynamic balance of the rotating parts of the vibrating device. The weights 62 and 63 perform the same function and purpose as the weights 62 and 63 of Fig. 2. Compensating rings 69 are provided on the stub shafts 135, and those rings rotate within the openings 156 of housing 158 and the central openings of cover plates 70. Oil slingers 71 are secured to the shaft elements 153 to force oil outwardly from those elements into the recessed cover plates 70. Openings 116 are provided adjacent the bottoms of recessed cover plates 70 to permit the flow of oil from those cover plates to the housings 158.

The shaft elements 153 also carry bearing housings 54 which have interiors and exteriors that are eccentric to each other. These bearing housings support housings 33, which housings extend downwardly to the cross-jack shaft assembly within housing 52b. That assembly includes the shaft 28, the bracket 52a, the bearing 52, the end 52f of the arm 52c, and the resilient bearing ring 52g. The cross-jack shaft 28 carries a sheave 29, and that sheave drives the sprocket gears 157 on the opposite ends of shaft 28. The gears 157 are connected by sprocket chains 159 to the sprocket gears 161 mounted on shaft elements 153; and thus power is applied to the discs 144 and 146. When this arrangement, the decks or supporting surfaces of the vibrating device are free from obstruction or interference. The vibrating device shown in Fig. 6 is a less expensive type of vibrating device than that shown in Fig. 2. However, that vibrating device is fully operative, and it will be

adequately lubricated because the sprocket gears and the discs will be capable of picking up oil in the bottoms of the several housings and splashing it about to effect complete lubrication of the device.

Fig. 7 shows a vibrating device which is similar to the construction shown in Fig. 6; the principal differences between the two constructions being that the cross-jack shaft assembly extends between and is supported by the side walls 113 of the vibrating device. The hubs 142 of discs 144 carry the sprocket gears 157, the shaft 28 carries the sprocket gears 161, the left hand shaft element 153 carries the sheave 29, the cross-jack shaft 28 vibrates with the decks or supporting surfaces of the vibrating device, and a single housing 165 replaces the two housings 33 and 158 of Fig. 6.

In each of the various vibrating devices disclosed herein, the cross-jack shafts are radially spaced from, rather than positioned between, the eccentric discs located at the sides of the body structures of the vibrating devices. As a result, an unusually large volume and area is provided on the supporting surfaces or decks of the vibrating devices to receive large and bulky objects and materials. Even in Fig. 7, where the cross-jack shaft assembly is supported by the side walls of the body structure, unusually large objects can be accommodated. By following the principles and teachings of the present invention, considerably increased capacity is made available. Moreover, in those instances where the cross-jack shaft assemblies are supported independently of the body structures, the body structures can be vibrated more freely and with less consumption of power.

Whereas several embodiments of the present invention have been shown and described in the drawing and accompanying description it should be apparent to those skilled in the art that various changes can be made in the form of the invention without affecting the scope thereof.

What I claim is:

1. In a vibrating device, a resiliently supported vibratable body, a vibration-imparting mechanism operatively connected to said body to produce gyratory displacement of said body, a casing supported on said body and enclosing said mechanism, said casing having an opening therethrough, a driving connection for said mechanism including a shaft element extending through said casing opening, an oil seal adjacent the said opening in said casing that permits displacement of the casing relative to said shaft element while preventing loss of oil, and a cross shaft driven by said driving connection, said cross shaft being radially spaced from said vibration-imparting mechanism.

2. In a vibrating device, a resiliently supported vibratable body, rotary mechanism connected to said body and adapted, when rotated, to produce

gyratory displacement of the body, a casing that encloses said rotary mechanism to permit splash lubrication of the latter and is supported on said body to follow the gyratory movements of said body, said casing having an opening therethrough, a shaft element projecting through said casing opening for operative connection to said rotary mechanism, said rotary mechanism being adjustable to change the amplitude of vibration of said body and simultaneously change the position of the axis of said shaft element relative to said opening in said casing, and a compensating ring that encircles said shaft element and fits within said opening in said casing, said compensating ring having a circular inner periphery and a circular outer periphery that are eccentric to each other.

3. In a vibrating device, a movable body, a resilient mounting for said body, rotatable eccentrics that are connected to the sides of said body and are effective for producing vibratory gyration of said body, and a connecting shaft for said eccentrics that is supported independently of the body and wholly externally thereof, said connecting shaft being spaced radially from said rotatable eccentrics.

4. In a vibrating device, a movable body, a support for said body, a plurality of shaft elements fixedly secured to said body, a second set of shaft elements that are supported for rotation relative to said body and have their axes of rotation off-set from the axes of rotation of said first shaft elements, eccentrically weighted discs that are rotatably journaled on the first shaft elements and are driven by said second shaft elements, and a driving connection that is external of said body and maintains said second shaft elements in register.

5. In a vibrating device, a resiliently supported body, a drive shaft located externally of said body, rotary members connected to said body and driven from said drive shaft for effecting gyratory displacement of the body, and a shaft supporting arm pivotally mounted independently of said body and extending substantially normally to the axis of said drive shaft to provide floating support for said drive shaft.
